United States Patent Office

Des. 176,726
Patented Jan. 24, 1956

176,726

COASTER OR SIMILAR ARTICLE

Joseph Matys, Brimfield, Mass.

Application February 16, 1955, Serial No. 34,536

Term of patent 14 years

(Cl. D44—10)

Fig. 1 is a plan view of a coaster or similar article, showing my new design; and

Fig. 2 is a view in side elevation thereof, looking in the direction of arrow 2 in Fig. 1.

I claim:

The ornamental design for a coaster or similar article, as shown.
